UNITED STATES PATENT OFFICE.

PETER L. JACKSON, OF BOONTON, NEW JERSEY.

DESIGN FOR A TOY.

SPECIFICATION forming part of Design No. 32,982, dated July 24, 1900.

Application filed June 7, 1900. Serial No. 19,473. Term of patent 7 years.

To all whom it may concern:

Be it known that I, PETER L. JACKSON, a citizen of the United States, residing at Boonton, in the county of Morris and State of New Jersey, have invented and produced a certain new and useful Design for a Toy; and I do declare the following to be a full, clear, and exact description of the invention, such as will enable others skilled in the art to which it appertains to make and use the same, reference being had to the accompanying drawings, which form a part of this specification.

This invention relates to a new and useful design for a toy, of which the following is a specification, reference being had to the accompanying drawings, forming a part thereof.

Figure 1 is a perspective view of a sounding toy embodying my design, and Fig. 2 is a side elevation of the toy.

As shown in the drawings, the design consists in the body portion of the toy having parallel sides, the free ends of which are in-

clined at an angle less than a right angle, and the projecting bottom of the toy beyond the free ends of the sides of the toy having rounded corners. The top portion of the toy is recessed between its side walls and has its projecting end slightly upwardly inclined from the inclined ends of the sides of the body portion of the toy, and the outer corners are rounded, and in the upper surface of the top of the toy opposite the upper inclined ends of the side walls is concaved.

Having thus described my invention, what I claim as new, and desire to secure by Letters Patent, is—

The design for a toy, as herein shown and described.

In testimony whereof I affix my signature in presence of two witnesses.

PETER L. JACKSON.
